UNITED STATES PATENT OFFICE.

JAMES BIRDSALL CALKINS, OF AUBURN, NEW YORK, ASSIGNOR TO MARCUS E. CALKINS, OF ITHACA, NEW YORK.

WINDING APPARATUS.

Application filed April 16, 1923. Serial No. 632,373.

To all whom it may concern:

Be it known that I, JAMES BIRDSALL CALKINS, a citizen of the United States of America, of Auburn, in the county of Cayuga, in the State of New York, have invented new and useful Improvements in Winding Apparatus, of which the following, taken in connection with the accompanying drawings, is a full, clear, and exact

10 description.

This invention relates to certain improvements in winding apparatus, and is here illustrated in its adaptation to spinning jennies, altho it is applicable for use in connection with roving frames, spinning frames, twisting frames, formers, layers or twisters, in which the product, while being revolved around a common axis to give it its twist, is presented to the coil, cop or ball and 20 wound thereon.

The apparatus illustrated is peculiarly adapted for winding twine, thread, yarn, rope, or the like in cylindrical, conical or otherwise shaped coils, and in such a manner that the ends of the coils will be self supporting and so that the distance between any two successive turns of the twine, etc., will be substantially the same regardless of the diameter of the coil or ball. In order to 30 obtain a coil or ball of twine, etc., of desired density and uniformity of winding, it has been customary in the use of spinning jennies and other apparatus to first wind the twine on bobbins with disks or heads at each 35 end thereof to keep the loops of twine from coming off the end of the coil or ball and subsequently the twine was delivered from the bobbin to other winding mechanism for producing the desired coil or ball preferably 40 of a character having self-supporting ends.

Certain of the advantages of this invention reside particularly in the elimination of the re-winding step and in the production of an apparatus by means of which the desired winding can be effected directly as the 45 twine is delivered from the twisting or spinning equipment, which desired winding may include the self-supporting character of the ends of the coils if that is desired.

Further, the invention avoids the necessity of using headed bobbins or spools and permits the use of a collapsible or other core of paper, wood or the like and the omission of the bobbin admits in many cases of the winding of larger or more suitably shaped coils or balls, thus eliminating much re-winding and doffing.

Other objects and advantages relate to the details of form, construction, arrangement and operation of the apparatus, all as will 50 more fully appear from the following description, taken in connection with the accompanying drawings, in which:

Figure 1 is an elevation of a spinning jenny combined with the winding device of 55 this invention.

Figure 2 is a vertical sectional view of a portion of the spinning jenny and the winding device.

Figure 3 illustrates the laying device.

Figure 4 is a view of the traverse fork.

Figure 5 is a view of a portion of the traverse screw.

Figure 6 illustrates a finished coil as it may be wound by the apparatus of this invention.

In order to specifically illustrate the construction and operation of this invention, it has, as above suggested, been disclosed in connection with a type of spinning jenny 60 commonly used for spinning hemp or sisal fibre, but it will be understood that this invention is in no way limited or restricted by this illustrative disclosure.

The operation of portions of the apparatus disclosed is that ordinarily used and well known in connection with spinning jennies. By means of the constant rotative movement of the capstans —3— driven by belt —4—, pulley —5—, shaft —13— and 65 spur gears —6—, —7—, and —8—, the fibre —1— is drawn through the usual nipper —2—. At the same time by means of the constant rotative movement of the flyer —9— driven by belt —10—, pulley —11—, and concentric shaft —20—, the fibre is 70 twisted in the nipper —2— and appears at the point —12— in twisted form.

From the nipper —2— the twine passes through a conduit or passageway in the center of the shaft —13— and around the capstans —3— and over the sheaves —14— 5 and —15— to the laying device —16— and on to the coil winding cylinder —17—. The operation of the structure so far described is well known. The coil winding cylinder —17— is axially supported by the removable 10 shaft —18— and is connected to the tubular shaft —19— for simultaneous rotation therewith in the usual manner as best illustrated in Figure 2, the shaft —18— being mounted within and carried by the tubular shaft 15 —19—.

The well known practice of "universal winding" for which the apparatus of this invention is adapted consists of winding the twine in a coil with a comparatively large 20 pitch or distance between each successive turn, and also advancing by approximately the width of the twine each successive traversal of the winding as illustrated in Figure 6, thus producing an interlocking 25 effect which makes the coil self-supporting, and eliminates the necessity of the headed bobbin or spool. To produce this effect with each successive layer of twine on a coil which is constantly growing larger, it is 30 evident that the coil winding cylinder —17— must be moved transversely in front of the laying device —16—, and this traverse motion must be always proportional to the 35 number of turns of the twine that are wound on the coil in a given increment of time. In other words, regardless of the diameter of the coil, the traverse must be moved the same distance for each turn wound upon the coil. However, since the twine is made 40 at a constant rate of speed and delivered by the flyer —9— at a constant rate of speed, the turns of twine wound on the coil in a given increment of time must always be inversely proportional to the variable diameter of the coil during that time interval, 45 and therefore, the traverse movement of the coil is inversely proportional to the diameter of the coil as well as directly proportional to the number of turns wound on the coil in 50 the given increment of time.

The twine imparts some of the rotative movement of the flyer —9— to the coil winding cylinder —17— and the tubular shaft —19— having the traverse screw 55 —32— formed thereon, and this amount is equal to the constant rotative speed of the flyer minus the number of turns of twine which have been wound on the coil in the given increment of time. In order to produce the type of winding desired and described heretofore, the traverse movement of the coil must always be proportional to the number of turns of twine wound on the coil in the given increment of time, regardless of the diameter of the coil. 60

For the purpose of producing the desired speed of traverse movement of the shaft —19—, the disk —22— is mounted on the shaft —19— and keyed thereto as by key —21— for simultaneous rotation therewith, 70 while permitting free reciprocation of the shaft —19— within the disk by reason of the elongated keyway —23— formed in the shaft —19—. The disk —22— is provided at an eccentric point thereon with a transverse opening for the reception of bearing —24— carrying a short shaft —25— which has its opposite ends projecting from the disk —22— and the bearing —24— and the respective projecting end portions carry 75 spur gears —25— and —27— both gear —26— and —27— being connected to the shaft —25— for simultaneous rotation with the shaft and with each other. The gear —26— meshes with the spur gear —28— 80 which is formed with a flange —60— engaged and connected to the hub of pulley —11— for producing simultaneous rotation of gear —28— and pulley —11— so that the gear —28— is rotated at the speed 90 of the flyer —9—, the flyer being mounted upon the tubular journal —61— upon which journal the pulley —11— is also mounted, and to which journal the pulley is keyed, as by key —62— and the flyer is keyed as 95 by —63—. It will be obvious that the pulley —11— drives both the flyer —9— and the gear —28—, the gear —28— being free to rotate upon and with respect to shaft 100 —19—.

Now, since the gear —26— is revolved by the disk —22— as driven by coil-winding cylinder —17— and shaft —19—, and at the same time gear —26— engages gear —28— rotating at the speed of the flyer, 105 —9—, the shaft —25— will be rotated at a speed proportional to the difference between the two speeds, (that is, the speed of the flyer and the speed of the shaft —19—) multiplied by the gear ratio. This difference is found to be proportional to the 110 number of turns of twine wound on the coil in a given increment of time, which in turn is proportional to the traverse movement of the cylinder —17— and the coil carried 115 thereby.

Through gear —27—, driven by shaft —25— and engaging with spur gear —29—, the rotative movement of the shaft —25— is compounded by the gear ratio and added 120 to the rotative speed of the disk —22—, causing gear —29— and the long sleeve —30— in connection with which such gear is formed, to rotate at a higher speed than the winding shaft or screw —19—, but at 125 a speed always proportional to the difference in speed between the flyer —9— and the coil-winding cylinder —17— plus the speed of the coil winding cylinder —17—. Mounted in or affixed to the sleeve —30— 130

journalled on shaft —19— is a traverse fork —31— which engages the threads of the right and left hand screw —32— cut on the winding shaft —19—. The traverse fork —31— and the traverse screw —32— both rotate in the same direction, but at different speeds as pointed out above, and, the difference between these two speeds taken in conjunction with the action and ratio of gears —23—, —26—, —27— and —28—, and the pitch of the traverse screw —32— produces the desired traverse movement of the shaft —19— and the coil-winding cylinder —17—. To better demonstrate this point, let F represent the rotative speed of the flyer —9— and therefore the gear —28—, and W the rotative speed of the coil-winding cylinder —17— and the shaft —19— with the traverse screw —32— cut thereon. Also let C represent the product of the ratios of gears —23—, —26—, —27— and —28—.

Therefore, using these symbols, the rotative speed of the traverse fork —31— will be $[(F-W)C+W]$, and the rotative speed of the traverse screw —32— will be W. The difference between these two speeds may be symbolized as

$$\{(F-W)C+W\} - W,$$

which algebraically reduces to $(F-W)xC$. But $F-W$ representing the speed of the flyer —9—, minus the speed of the coil-winding cylinder —17— equals the number of turns of twine wound on the coil in the given increment of time, and therefore, as proven heretofore, is proportional to the desired traverse movement of the coil winding cylinder —17—. Thus, as determined by the ratio of the gears and the pitch of the traverse screw, any desired pitch of winding may be accomplished. Further, by proper selection of the relative proportions of gear ratios and length and pitch of traverse screw, each successive traversal will be advanced if that is desired by a proper amount, so that the twine will be laid in a hard, smooth coil, as illustrated in Figure 6.

Purely for the purpose of illustration, the gear —28— may have 46 teeth, while the gear —26— has 12 teeth, and the gear —27— may have 33 teeth, while the gear —29— has 25 teeth for producing the desired relative speeds of the parts with which they are associated in driving relation.

In order to provide sufficient tension in the twine so that it will be wound in a hard, smooth coil, suitable means should be provided for resisting the rotary movement of shaft —19— to a desired extent, and for that purpose, and as illustrative of one such means adapted for effecting it, the disk —22— is provided with a pulley face —33—

adapted for driving a belt —35— and thus imparting a rotary movement to the pulley —36—. The shaft —39— drives in the same direction as the pulley —36— but at a slightly lower rotative speed. Thus, through the medium of spring —38— and the disk —37— bearing against the web or side of the pulley —36—, a retarding effect is induced in the belt —35— and transferred through the medium of pulley —33— to the shaft —19— and to the winding cylinder —17—. By adjusting the tension of the spring —38— any desired retarding effect may be produced for properly tensioning the twine during the winding of the coil.

It will be understood from the above description that the flyer —9— is driven at a substantially uniform rate of speed and that the hollow shaft —19— is driven by the twine or thread as it is laid upon the winding cylinder —17— at a rate of speed somewhat slower than that of the flyer, and that these two rotative speeds are so correlated and applied to the traverse screw of the shaft —19— by means of the traverse fork as to effect the traverse movement of the shaft —19— at a speed varying in accordance with the requirements for the production of an effective coil or ball which may, if desired, be of the character known as "universal wind," as illustrated in Figure 6. Altho I have shown a specific application of my invention to a particular machine, together with perhaps preferred details, of form, construction and arrangement, I do not desire to restrict myself to any particular application of the invention, or to the details of form, construction or arrangement of the same, except as the same may be specifically required by the claims hereto appended.

I claim:

1. In an apparatus of the character described, a delivering element driven at a constant rate of speed, a receiving element, a rotary shaft connected to the receiving element and rotating therewith, a disk rotating with the rotary shaft, a gear journaled on an eccentric portion of said disk, a second gear meshing with the first-named gear, means for driving the second gear at a rate of speed corresponding to the speed of the delivering element, and means driven by the first-named gear for causing a traversing movement of the said shaft during its rotary movement.

2. In an apparatus of the character described, a delivering element driven at a constant rate of speed, a receiving element, a rotary shaft connected to the receiving element and rotating therewith, a disk rotating with the rotary shaft, a gear journaled on an eccentric portion of said disk, a second gear meshing with the first-named

gear, means for driving the second gear at a rate of speed corresponding to the speed of the delivering element, a third gear mounted on the same axis as the first-named gear, and rotated by the first-named gear, and means actuated by the last-named gear for causing a traversing movement of said shaft.

3. In an apparatus of the character described, a delivering element driven at a constant rate of speed, a receiving element, a rotary shaft connected to the receiving element and rotating therewith, a disk rotating with the rotary shaft, a gear journalled on an eccentric portion of said disk, a second gear meshing with the first-named gear, an elongated sleeve mounted on the shaft, a gear in connection with said sleeve, said gear in mesh with the third gear for driving the sleeve, and means carried by the sleeve for causing a traversing movement of said shaft.

4. In an apparatus of the character described, a delivering element driven at a constant rate of speed, a receiving element, a hollow shaft concentric with the delivery element, a rotary gear loosely mounted on said shaft, and means cooperating with said gear for causing a traversing movement of said shaft.

5. In an apparatus of the character described, a delivering element driven at a constant rate of speed, a receiving element, a hollow shaft concentric with the delivery element, a rotary gear loosely mounted on said shaft, means driven by the shaft and cooperating with said gear for causing a traversing movement of said shaft.

6. In an apparatus of the character described, a delivering element driven at a constant rate of speed, a receiving element, a hollow shaft concentric with the delivery element, a rotary gear loosely mounted on said shaft, a disk mounted on and rotatable with said shaft, a gear eccentrically mounted on said disk and meshing with the first-named gear, and means cooperating with the second-named gear for causing a traversing movement of said shaft.

50 7. In an apparatus of the character described, a delivering element driven at a constant rate of speed, a receiving element, a hollow shaft concentric with the delivery element, a rotary gear loosely mounted on said shaft, and means driven by said shaft including a revolving gear for causing a traversing movement of said shaft.

8. In an apparatus of the character described, a delivering element, a receiving element, a rotary and reciprocable shaft connected to the receiving element, and a differential mechanism mounted on said shaft and a portion of the same rotating at the speed of the shaft and a portion of the same rotating at the speed of the delivering

element for causing a traversing movement of said shaft.

9. In an apparatus of the character described, a delivering element, a receiving element, a rotary and reciprocable shaft connected to the receiving element, a differential mechanism mounted on said shaft, a portion of which mechanism rotates with and at the speed of the shaft and another portion of which mechanism rotates with and at the speed of the delivering element, and means actuated by the differential mechanism for causing a traversing movement of said shaft.

10. In an apparatus of the character described, a delivering element, a receiving element, a rotary and reciprocable shaft connected to the receiving element, said shaft having a portion formed with a traverse screw, a differential mechanism mounted on said shaft and including a part rotating at the speed of the shaft and another part rotating at the speed of the delivering element, a sleeve rotatably mounted on said shaft and driven by said differential mechanism, and a traverse fork carried by said sleeve and engaging the traverse screw upon the shaft.

11. In an apparatus of the class described, a winding shaft having a traverse screw formed thereon, a sleeve rotatably mounted on said shaft, a flyer secured to said sleeve for simultaneous rotation therewith, means for rotating the sleeve, a gear mounted on said sleeve and rotating with and at the speed of the flyer, a disk splined to said shaft, a gear rotatably mounted upon an eccentric portion of said disk and in mesh with the first-named gear, a second elongated sleeve mounted on said shaft, a traverse fork carried by said second sleeve and engaging the traverse screw upon said shaft, and means driven by the last-named gear for rotating said second sleeve to cause a traverse movement of said shaft.

12. In an apparatus of the class described, a delivering element, a receiving element, a rotatable shaft connected to the receiving element, and means for causing a traverse movement of said shaft including a gear revolving about the shaft.

13. In an apparatus of the class described, a delivering element, a receiving element, a rotatable shaft connected to the receiving element, means for causing a traverse movement of said shaft including a gear revolving about the shaft, a gear rotatably mounted on the shaft, and means for driving the last-named gear at the speed of the receiving element, plus the difference in speed between the delivery element and the receiving element.

14. In an apparatus of the class described, a delivering element, a receiving element, a rotatable shaft connected to the receiving element, means for causing a traverse move-

ment of said shaft, including a gear revolving about the shaft and a means tending to retard the rotation of said shaft.

15. In an apparatus of the class described, a delivering element, a receiving element and a traversing mechanism wherein one function rotates at a speed proportional to the difference between the rotative speed of

the delivering element and the receiving element, plus the speed of the receiving element, and the other function rotates at a speed proportional to the receiving element. ¹⁰

In witness whereof I have set my hand this seventh day of April 1923.

JAMES BIRDSALL CALKINS.
